UNITED STATES PATENT OFFICE.

LOUIS E. PITTONI, OF JAMAICA, NEW YORK, ASSIGNOR TO THE ROME COMPANY, INC.,
A CORPORATION OF NEW YORK.

INTERLOCKED HELICAL SPRING.

Application filed April 11, 1927. Serial No. 182,988.

The present invention relates to spring cushions and particularly to that type of cushion in which there are vertical spiral springs whose upper turns or rings are tied together by crossed small helical springs. The object of the present invention is to bring about in a simple manner a locking together of the tie springs to prevent relative displacement thereof out of the plane containing them.

In an application of Darwin Hanauer, Serial No. 171,059 the need for fastening the tie springs together is explained and means for accomplishing that purpose are disclosed. In one of its aspects the present invention may be regarded as comprising a specific form of the invention set forth in the aforesaid application.

The various features of novelty whereby the present invention is characterized will hereinafter be pointed out with particularity in the claim; but, for a full understanding of the present invention and of its objects and advantages, reference may be had to the following detailed description taken in connection with the accompanying drawing, wherein:

Figure 1 is a plan view of a fragment of a spring cushion embodying the present invention; Fig. 2 is an elevation on a larger scale of the middle section of one of the tie springs; Fig. 3 is a plan view of the tie springs, interlocked; and Figs. 4 and 5 are sections taken respectively on lines 4—4 and 5—5 in Fig. 3.

Referring to the drawing, 1, 2, 3 and 4 represent fragments of the top coils or rings of four adjacent main spiral springs in a spring cushion. These four rings are tied together by two small intersecting helical springs 5 and 6 whose ends are fastened to the rings of the main in any suitable way. The tie springs are interengaged by screwing one through the other. In order to prevent relative displacement of the tie springs out of the plane containing them, and consequently the noises and damage resulting therefrom, the middle coil of one of the

springs is provided with a notch or seat 7 to receive a coil of the other spring. This notch or seat is produced by making a sharp inward bend in the wire.

When the two springs are to be interengaged, one end of the spring 6 is screwed into the spring 5 at such a point that the wire of the spring 6 will enter the notch 7 instead of passing on the inner side of the spring 5 at that point as would be the case if there were no notch. Then, after the interengagement of the springs has been completed, it will be found that one of the coils of the spring 6 rests in the notch in the other spring while the next coil bears against the inner side of the wire of the spring 5 near the notch, as best shown in Fig. 4. Now, if the spring 6 tries to move up, the coil marked A in Fig. 4 will carry the spring 5 up with it. If the spring 6 tries to move down, the coil marked B in Fig. 4, namely the one seated in the notch of the spring 5, pulls the other spring down. Therefore, although the spring 5 may roll about the notch as a fulcrum, there can be no slipping up or down of either tie spring relatively to the other when assembled in the spring cushion.

Although only a single preferred form of the present invention has been illustrated and described, the invention is not limited to the exact structural details thus illustrated and described; but covers all forms and arrangements coming within the definitions of the invention constituting the appended claim.

What is claimed as new is:

Two interengaged crossed helical springs one of which has a peripheral notch in the wire thereof, the other spring having a coil outside of the wire of the first spring and seated in said notch and a second coil extending through the interior of the first spring and engaged with the wire of the latter near said notch.

In testimony whereof, I sign this specification.

LOUIS E. PITTONI.
